CLAIM

We claim the ornamental design for a soundbar, as shown and described.

DESCRIPTION

FIG. 1 shows a first perspective view of the soundbar;
FIG. 2 shows a second perspective view of the soundbar;
FIG. 3 shows a front view of the soundbar;
FIG. 4 shows a rear view of the soundbar;
FIG. 5 shows a first side view of the soundbar;
FIG. 6 shows a second side view of the soundbar;
FIG. 7 shows a top view of the soundbar; and,
FIG. 8 shows a bottom view of the soundbar.
The portions shown in broken lines form no part of the claimed design.
